UNITED STATES PATENT OFFICE.

HOWARD B. LOVEJOY, OF SEATTLE, WASHINGTON.

FUEL MIXING AND GASIFYING DEVICE.

1,201,976.

Specification of Letters Patent. Patented Oct. 17, 1916

Application filed October 18, 1915. Serial No. 56,631.

To all whom it may concern:

Be it known that I, Howard B. Lovejoy, a citizen of the United States, residing at Seattle, in the county of King and State of Washington, have invented a new and useful Improvement in Fuel Mixing and Gasifying Devices, of which the following is a specification.

This invention relates to improvements in devices for mixing and gasifying low grade fuel for use in internal combustion engines and the object of this improvement is to provide a device that may be introduced between the engine and its carbureter and wherein a low grade of fuel such as crude oil may be mixed and heated to a high temperature to thoroughly atomize and gasify the same before it is admitted to the cylinders of the engine for combustion.

The invention consists in the novel construction of fuel mixing and gasifying devices and the adaptation of such devices to an internal combustion engine and its carbureter as will be more clearly described in the following specification, illustrated in the accompanying drawings and finally pointed out in the appended claims.

In the accompanying drawings Figure 1 is a view in vertical mid-section of a device embodying my invention; Fig. 2 is a view in horizontal cross section on broken line 2, 2 of Fig. 1.

The device herein disclosed is in actual operation on a marine engine adapted to burn distillate and it is found that when this device is used the engine will run very satisfactorily on a low gravity oil that is very much cheaper than distillate.

Referring to the drawings throughout which like reference numerals indicate like parts the numeral 3 indicates the outer wall of a fuel mixer that is preferably constructed with an integrally formed inner wall 4 spaced within the outer wall to form an annular passageway 5 therebetween through which heated exhaust gases from an internal combustion engine (not shown) may be caused to pass.

The device is provided with a cover plate 6, secured thereto by set screws 7 and threaded for the reception of a pipe 8 that

is directly connected with the fuel inlet port of an internal combustion engine. The bottom side of the casing is threaded for the reception of a fuel inlet pipe 9 that 55 leads directly from a carbureter, (not shown) and the sides of the outer wall 3 are provided at diametrically opposite points with bosses 10 that are threaded for the reception of pipes 11 and 12, one of the pipes 60 as the pipe 11 being directly connected with the exhaust port of the engine and the other pipe 12 being the pipe through which the exhaust gases escape into the atmosphere.

An annular ring or washer 14 is secured 65 within the upper portion of the device by inserting the peripheral edges of such washer in suitably formed notches in the wall 4 and then clamping the cover plate securely on top of it. A plurality of 70 depending brackets 15 are secured to the washer 14 and serve to support a circular deflector or target 16 in a concentric position within a mixing chamber 17 that is formed by the walls 4. The deflector 16 is 75 of considerably smaller diameter than the mixing chamber 17 and is located in a plane at right angles to the axis of the mixing chamber at a point about half way between the top and bottom thereof.

The lower end of the chamber 17 is formed with converging or conically shaped walls 18, herein shown as disposed at an angle of about forty-five degrees, and within which are provided a plurality of perforations 20 that communicate with the chamber 5 and serve to direct a plurality of small jets of exhaust gas upwardly against the central portion of the deflector 16. A screen 21 of relatively fine mesh is interposed in 80 the passageway between the mixing chamber 17 and the fuel supply pipe 8 that leads to the engine such screen preferably having its edges secured between the washer 14 and the brackets 15.

In use the device herein shown is connected with the fuel supply pipe of an internal combustion engine between the engine and the carbureter and a low grade of fuel as crude oil is admitted to the carbureter. The 100 pipe 11 is connected with the exhaust pipe of the engine and the engine is then started

in the usual manner and as it runs draws the fuel from the carbureter through the mixing chamber 17. The heated exhaust gases from the engine will circulate through 5 the passageway 5 as indicated by the arrows A in Fig. 2 thus heating the walls of the chamber 17 to a high temperature and causing fine jets of the exhaust gases to pass upwardly through the perforations 20 into 10 the mixing chamber 17 and impinge on the deflector 16 as indicated by arrows B. At the same time fuel from the carbureter is being sucked in through the pipe 9 and is directed upwardly against the deflector 16. 15 The result is that a whirling movement and consequent mixing of the fuel and exhaust gas is produced, the fuel is directed outwardly against the heated walls of the chamber 17, is thoroughly atomized and 20 gasified and passes upwardly around the edges of the deflector 16 through the screen 21 and through the pipe 8 to the engine. The screen 21 insures that no foreign particles of solid matter will find their way into 25 the cylinder of the engine.

The device is easily assembled and taken apart, the removal of the cover plate 6 permitting the ring 14 and parts connected therewith to be lifted out and access to be 30 had to the interior of the mixing chamber.

The amount of exhaust gas admitted through the perforations 20 is not sufficient to dilute the fuel taken in through the mixer enough to appreciably lessen its efficiency, 35 the exhaust gas simply helping to atomize and gasify the crude fuel as it is drawn through the mixing chamber 17.

In some instances it may be found advantageous to provide an asbestos covering 40 for the mixing device and exhaust pipes to prevent them from presenting a heated exterior surface.

Obviously changes in the form of construction of my device may be made within 45 the scope of the claims.

What I claim is:—

1. A device of the class described comprising an outer casing, an inner casing spaced within said outer casing to form a 50 mixing chamber for fuel and a passageway for heated gases said inner casing having perforated walls, inlet and outlet pipes communicating with said passageway for heated gases, fuel inlet and outlet pipes communicating with said mixing chamber, and a deflector interposed in said mixing chamber in line with said fuel inlet pipe.

2. A device of the class described comprising an outer casing, an inner casing spaced within said outer casing to form a 60 mixing chamber for fuel and a passageway for heated gases said inner casing having converging perforated walls at its lower end communicating with said passageway for

heated gases, inlet and outlet pipes for exhaust gases communicating with said passageway, inlet and outlet pipes for fuel communicating with said mixing chamber, and a deflector interposed in said mixing chamber in line with said fuel inlet pipe. 65

3. A device of the class described comprising outer walls, inner walls spaced within said outer walls to form a passageway for heated gases therebetween, inlet and outlet exhaust pipes connected with said passageway, inlet and outlet fuel supply pipes connected with said mixing chamber, a deflector concentrically disposed within said mixing chamber in alignment with and in a plane at right angles to said inlet fuel supply pipe and perforations in said inner walls for admitting a plurality of jets of exhaust gas from said passageway into said mixing chamber. 70

4. A device of the class described comprising an inner casing inclosing a mixing chamber said inner casing having converging walls at the bottom end thereof that are perforated to direct a plurality of jets of gas upwardly and inwardly, a deflector in 90 said mixing chamber, a fuel inlet pipe communicating with said mixing chamber and connected with a carbureter, a fuel outlet pipe connecting said mixing chamber with an engine, a screen between said mixing 95 chamber and said fuel outlet pipe, an outer casing surrounding said inner casing and forming a passageway therebetween and inlet and outlet pipes for heated exhaust gases connected with said passageway.

5. A device of the class described comprising an inner casing inclosing a mixing chamber said inner casing having converging walls at the bottom end thereof that are perforated to direct a plurality of jets of gas upwardly and inwardly, a deflector in 105 said mixing chamber for said jets of gas to impinge upon, brackets supporting said deflector, a ring connected with said brackets, a cover for said casing adapted to clamp 110 said ring, a screen associated with said ring, a fuel inlet pipe, a fuel outlet pipe, an outer casing surrounding said inner casing, and forming a passageway there-between, an inlet pipe for heated gases and an outlet pipe 115 for heated gases.

6. A heater and gasifier for low gravity oil, comprising a casing having a mixing chamber and a passageway for heated gases, a deflector in said mixing chamber, and perforations in the wall between said mixing chamber and said passageway for heated gases to direct jets of heated gases into said mixing chamber. 120

7. A device of the class described comprising a casing having a mixing chamber for low gravity fuel and a separate passageway for exhaust gases, and a wall between 125

said mixing chamber and said passageway, said wall having perforations to direct jets of exhaust gases from said passageway into said mixing chamber to atomize and gasify

around said mixing chamber, said inner 10 wall having perforations formed therein.

Signed by me at Seattle Washington, this 4th day of October, 1915.

HOWARD B. LOVEJOY.
